UNITED STATES PATENT OFFICE.

CHARLES E. RICHARDSON, OF NEW YORK, WILLIAM BARTON EDDISON, OF IRVINGTON, AND HENRY L. READ, OF NEW YORK, N. Y., ASSIGNEES TO THE SURFACE COMBUSTION COMPANY, OF NEW YORK, N. Y., A CORPORATION OF NEW YORK.

METHOD OF BURNING EXPLOSIVE GASEOUS MIXTURES.

1,308,739.

Specification of Letters Patent.

Patented July 1, 1919.

Original application filed November 23, 1916, Serial No. 133,086. Divided and this application filed September 29, 1917. Serial No. 193,982.

To all whom it may concern:

Be it known that we, CHARLES E. RICHARDSON, WILLIAM BARTON EDDISON, and HENRY L. READ, citizens of the United States, residing, respectively, at New York city, county of New York, and State of New York; Irvington, Westchester county, New York, and New York city, county of Kings, New York, have invented certain new and useful Improvements in Methods of Burning Explosive Gaseous Mixtures, fully described and represented in the following specification and the accompanying drawings, forming a part of the same.

15 This invention relates to a method of burning explosive gaseous mixtures, and aims generally to reduce the pressure under which it is necessary to supply the explosive mixture to the discharge tubes or nozzles, to increase the range of heat production or amount of mixture burned with a limited maximum supply pressure, and to avoid the danger of backflashing through the supply passages under any operating conditions, but especially when operating with mixture supplied under relatively low pressures, and also to maintain the pressure-capacity characteristic of the burner tube or nozzle under varying supply pressures, this being desirable with some types of mixture supply means in order that the proportions of fuel and combustion supporting gas in the mixture shall be maintained constant.

20 The invention has to do with the method of combustion in which continuous and localized combustion of an explosive gaseous mixture is secured by causing the mixture to flow from a discharge passage or orifice with a velocity greater than the rate of propagation of inflammation of the mixture in order to prevent backflashing, and then causing the mixture to spread out with rapid reduction of its flow velocity and burning the mixture where its flow velocity

25 equals the rate of propagation of inflammation of the mixture. The spreading of the mixture may be caused by baffling means consisting of a porous and permeable bed of suitable highly refractory material, or other suitable means, located close to the discharge orifice so that the stream is caused to spread immediately as it leaves the orifice, or the mixture may be permitted to flow from the

30 orifice as an unconfined stream which impinges against a baffling means spaced off at a suitable distance from the discharge orifice, or the rapid spreading of the mixture may be caused in other ways.

35 By such continuous and localized combustion of explosive gaseous mixtures, extremely high temperatures are developed, and various practical difficulties have been experienced due to the heating of the walls of the mixture discharge passage or orifice. It is found that as the walls of the discharge passage or orifice become heated, combustion of a portion of the flowing mixture tends to take place within the mouth of the orifice and to gradually work back along the walls of the orifice or discharge passage while the main portion of the mixture is flowing on, unburned, to be consumed at the surface or place where its flow velocity has been reduced to the rate of propagation of inflammation. This "back-creeping" of combustion, which is a totally different thing from "back-flashing" through the body of the stream of mixture, probably results from the presence of a relatively slow moving thin layer or film of mixture against the walls of the discharge passage due to the frictional resistance exerted by the walls on the mixture flowing past them. If the edge of the discharge orifice becomes heated to a sufficient temperature, probably a temperature somewhat above the ignition temperature of the mixture, this relatively slow moving film of mixture becomes ignited at such point and combustion then travels backward along the walls for a distance and at a rate depending upon the temperature of the walls and the velocity at which the mixture is flowing through the passage. With increase in flow velocity of the mixture, the thickness of the relatively slow moving wall film is reduced and the cooling effect of the stream of mixture on such film and on the walls of the passage themselves increases, so that the back-creeping tendency decreases with such increase in flow velocity of the mixture, and with a sufficiently high flow velocity back-creeping may be stopped and combustion within the discharge passage or orifice entirely prevented. Prevention of such back-creeping in this way, however, means that continued

operation of the apparatus requires a relatively high mixture supply pressure.

This back-creeping of combustion along the walls of the supply passage is objectionable for a number of reasons: It causes more or less rapid deterioration of the walls of the discharge passages according to the material of which they are formed; by heating the stream of mixture flowing through the passage, it causes a development of back pressure or resistance to flow, which reduces the velocity with which the mixture is discharged under a given supply pressure, and which is objectionable with some types of means for supplying the mixture because of its effect in changing the proportions of the constituent gases in the mixture; and it causes ignition and explosion of the slower moving mixture in supply passages or chambers, when the back-creeping reaches such a passage or chamber. By reducing the velocity of discharge, the development of back-pressure or resistance to flow resulting from the heating of the mixture limits the reduction of supply pressure under which the apparatus will operate and restricts the range of operation under a given maximum supply pressure.

It is desirable, in order to reduce the resistance to flow of the mixture, that the discharge passage through which the mixture is caused to move with excess velocity to prevent backflashing, be relatively short, the mixture being supplied to such passage through a large passage in which the flow velocity is relatively lower. It is also desirable that the mixture be discharged through a short passage or orifice of such form that flow of mixture therethrough under varying pressures shall vary according to the flow law of orifices, and that pipe resistance as a controlling factor on the flow of the mixture be avoided. With such a short discharge passage or orifice, the danger of ignition of the mixture in the larger portion of the passage and backflashing therethrough is, of course, greatly increased, both from the back-creeping of combustion along the walls of the discharge passage or orifice, and also by the conduction of heat through the walls themselves.

It is the object of the present invention to avoid such back-creeping of combustion of any part of the mixture within the discharge passage or orifice even with a comparatively low mixture flow velocity, and this result is secured according to the present invention by maintaining the walls of the discharge orifice or passage at a temperature which is substantially lower than the ignition temperature of the mixture, by causing the heat reaching the nozzle, and which would otherwise accumulate and raise the walls of the discharge passage or orifice unduly, to be carried away with sufficient rapidity to prevent such result, and by so limiting the access of heat to the nozzle as to reduce the loss of heat and to reduce the burden imposed on the heat withdrawing means. For this purpose the circulation of a cooling fluid may be resorted to, but most desirably the nozzle is made of a suitable metal or other suitable material of high heat conductivity, if there is such other material, and of sufficient mass in all its parts which receive heat either from the furnace chamber or from the furnace wall or from other parts of the nozzle to have sufficient heat conducting capacity to conduct the heat received with sufficient rapidity to maintain the walls of the mixture passage at the desired low temperature, and is provided with fins or other means providing sufficient extended surface for the discharge of heat to the atmosphere or with other means for taking from it the heat conducted backward through its body portion. Whether or not the body of the nozzle of sufficient mass is depended on to conduct the heat from the exposed end of the nozzle back to the dissipating means, the walls of the mixture discharge passage or orifice should be of material of high heat conductivity, such as iron or other suitable metal. As such material not only conducts heat rapidly, but also rapidly absorbs heat, the nozzle is so far as possible protected from direct access of heat by a covering of material of relatively low heat conductivity, usually a part of the furnace wall of brick, cement or other refractory material, in which the nozzle is set. Such material, however, because of its low heat conductivity, becomes very highly heated under the intense heat of the combustion of the explosive mixture, the whole refractory wall of a furnace chamber usually becoming more or less highly incandescent. Contact of any part of such material, therefore, with the stream of mixture issuing from the nozzle orifice would result in ignition of the mixture at the edge of the orifice, and to avoid this, a part of the metal of the nozzle nose immediately surrounding the orifice is left uncovered, the width of such exposed portion of metal being sufficient to prevent contact of the issuing stream of mixture with, and ignition thereof by, the surrounding refractory material of the furnace wall by which the main portion of the nozzle is protected.

The accompanying drawings illustrate an approved form of apparatus by which the method may be practised, such apparatus being claimed in my original application Serial No. 133,086, filed November 23, 1916, Patent No. 1,242,114, granted October 2, 1917. In said drawings:

Figure 1 is a central sectional view of a soft metal melting furnace for burning ex-

explosive mixtures in accordance with the invention;

Fig. 2 is an enlarged sectional view of a part of one of the mixture discharge nozzles shown in Fig. 1 and adjacent portions of the furnace walls;

Fig. 3 is an outside end view of one of the nozzles shown in Figs. 1 and 2; and

Fig. 4 is a view similar to Fig. 2 but showing a form of water-cooled nozzle.

Referring to the drawings, and first to Figs. 1, 2 and 3, the furnace structure shown comprises a bottom wall or floor 10 and side walls 11 of brick-work, the brick wall 11 being inclosed within an outer metal casing 12 with an intermediate space between the metal and the brick filled with heat insulating material 13, such as powdered sil-o-cel.

Carried by a suitable support on the top 20 of the side walls 11, is a melting pot 15 which extends down into the furnace chamber between the side walls.

The explosive gaseous mixture to be burned is discharged from a plurality of discharge tubes or nozzles 20, of which two are shown in section in the drawings, mounted in the side wall 11 and set to direct the jet or stream of mixture issuing therefrom against a suitable baffling means by which 25 the mixture is caused to spread out with rapid reduction of its flow velocity. In the furnace shown the baffling means is spaced off from the nozzles so that the issuing streams of mixture are permitted to travel 30 from the nozzles to the baffling means as unconfined streams, and as shown the baffling means consists of a bed or beds 21 formed of pieces of refractory material arranged with the surface of the bed in suitable relation to the downwardly directed stream of 35 mixture so that the stream will be baffled and caused to spread out in the desired manner. Such a bed will be porous and permeable and will have the advantage of permitting the products of combustion to pass 40 through it and escape therefrom beyond the place where combustion takes place, and the combustion may take place at the surface of the bed or within the bed, according to the 45 size of the stream of mixture and the velocity with which it strikes the bed.

A furnace of this kind may be of any desired shape in horizontal section. The one shown is a circular furnace, the mixture discharge nozzles, of which there may be any desired or required number, being arranged radially in the cylindrical side wall 11.

The explosive mixture may be supplied to 60 the discharge nozzles under the necessary pressure to cause the mixture to be discharged with a velocity in excess of the rate of propagation of inflammation of the mixture from any suitable source or by any 65 suitable means. As shown, a mixing injec-

tor is provided for supplying an explosive mixture of fuel gas and air, the gas being supplied to the injector nozzle 25 under suitable pressure and air being drawn into the combining tube 26 of the injector by the 70 gas jet, and the gas and air then passing through the neck of the injector and through the discharge or pressure cone 27 to a supply pipe or manifold 28 from which branches 29 lead to the several nozzles 20. The injector should be designed, and the 75 nozzle and combining tube set in proper relative position, as by adjusting either one, to supply a mixture containing the gas and air in suitable proportions, and the gas 80 should reach the injector under sufficient pressure to cause the mixture as supplied to the nozzles to flow through the discharge orifices of the nozzles with a velocity in excess of the rate of propagation of flame 85 through the mixture. The manifold 28 and supply branches 29 should be large enough to permit the mixture to move therein with such comparatively low velocity as to secure a substantially uniform supply of mixture to all of the nozzles, and to avoid pressure losses due to pipe friction.

The nozzles 20 are formed each with a bore or passage 33 extending through the body of the nozzle of a size which is most desirably substantially greater than the size of the discharge orifice, and this passage tapers down at the front or discharge end of the nozzle and terminates in a restricted short discharge passage or orifice 36 which 95 desirably has parallel walls for a length sufficient to cause the mixture to be discharged in the form of a solid jet or stream. The nozzle is formed of material of high thermal conductivity, such as cast-iron or other 100 suitable metal, and is made of sufficient cross-section or mass so that all parts thereof shall have the required heat conducting capacity for carrying away at the necessary rate all heat reaching such part. It is set 105 in the furnace wall and protected by the wall from direct access of the furnace heat, except for a limited portion of its discharge end or nose adjacent the orifice. The end of the nozzle is most desirably tapered as 110 shown, and has a blunt edge to provide a flat narrow annular face 37 about the orifice to be left uncovered and exposed to the furnace heat.

It is desirable to have the nozzle protected 115 so far as possible from direct access of furnace heat, both for the purpose of keeping down to a minimum the loss of heat through the nozzle walls, and to avoid unduly increasing the size of the nozzle to give it the 120 necessary heat carrying capacity. On the other hand, it is necessary, as pointed out ante, that there shall be some extent of metal about the edge of the discharge orifice exposed to direct access of heat from the fur- 125 130

nace chamber, in order to prevent contact with the stream of mixture of any material of relatively low heat conductivity forming part of the furnace wall. Because of its low 5 heat-carrying capacity, the refractory material of the furnace wall, under the intense heat developed, becomes extremely hot, usually incandescent. The exposure of any sufficient extent of the metal of the nozzle about 10 the edge of the orifice prevents contact of such incandescent material with the mixture and avoids the ignition of the mixture at the edge of the orifice with increase in temperature at this point and increased tendency to back-creeping which would result 15 from such contact.

The exact width or extent of metal left uncovered at the nose of the nozzle is not particularly important, provided it is sufficient to secure the desired result, but in order 20 to avoid loss of heat and the necessity of providing for the carrying away of such excessive amount of heat, it is most desirably not much wider than is necessary to protect the mixture from the incandescent material.

We have usually found it desirable to set the nose of the nozzle slightly back from the face of the furnace wall in a small recess formed in the face of the wall, with the nose 30 of the nozzle extending somewhat into the recess, and then partly filling in the recess about the nozzle nose with a suitable refractory cement, as indicated at 40, having the cement extend not beyond the outer edge of 35 the annular face at the end of the nozzle and forming it to flare suitably away from the path of the mixture stream. The cement should be carefully placed to form a tight joint with the end of the nozzle so that it 40 may not only protect the same from direct access of heat, but also by sealing the space between the nozzle and the brick-work prevent the hot furnace gases from flowing in around the nozzle, although this is not necessary provided the nozzle is otherwise suitably sealed in the wall so as to prevent the flow of the furnace gases past it. The nozzle is desirably formed with a tapering nose as 45 shown having near its discharge end projections 41 of suitable form to provide a hold for the cement 40.

For taking from the nozzle the heat conducted from its exposed portions backward through its body portion, the nozzle is provided with heat dissipating fins 42 formed on its rear end outside the furnace wall, such fins providing extended surfaces of sufficient extent to discharge to the atmosphere all the heat reaching them through the body of the 50 nozzle with sufficient rapidity to prevent such accumulation of heat in any part of the nozzle as would result in an undue increase in temperature of any such part. The fins may be of any suitable form. Flat angular tapering fins of about the proportion-

ate size shown in the drawings on nozzles made of cast-iron have been found entirely satisfactory under various conditions of operation, and make the provision of special means, such as means providing a circulating fluid for carrying away heat from the nozzle, wholly unnecessary. The nozzle may be secured to the outer casing of the furnace wall by means of a plate 43 formed on the nozzle, as shown, this plate also serving 75 as an additional heat dissipating means.

Fig. 4 shows a form of water-cooled nozzle consisting of a comparatively thin-walled mixture tube 50 provided with a tapered nose piece 51 formed to provide a restricted discharge orifice, and a metal casing 52 extending about the tube 50 and connected with the edges of the nose piece 51, the space between the mixture tube and the casing being divided by a partition tube 53 which ends short 80 of the front end of the casing so as to provide concentric supply and return flow passages for water or other cooling fluid which is supplied and discharged through pipes 55 and 56. This jacketed nozzle may be set in 85 the furnace wall in substantially the same manner as the air-cooled nozzle shown in Figs. 1 to 3, the front end of the nozzle being protected more or less from direct access of furnace heat by a protecting covering formed 90 by a filling of cement or other part of the furnace wall, such protecting covering ending short of the edge of the discharge orifice as shown at 1 for the purposes hereinbefore described.

It will be understood that by the term "explosive gaseous mixture" as used herein is meant a mixture of a suitable combustion supporting gas, either oxygen alone or air or other oxygen-containing gas, with combustible matter in a gaseous or other finely divided state in proper proportions, that is, in proportions such that the mixture will have the property of self-propagation of inflammation. For producing the highest temperature, the oxygen should be undiluted and the mixture should contain oxygen and combustible matter in chemical combining proportions at the time of combustion; but there may be an excess of either the combustible matter or the combustion supporting gas within the limits which determine the property of self-propagation. The mixture may be varied in this respect according to the desired character of the products of combustion, that is, whether it is desired that the products shall be neutral, oxidizing or reducing. Also, the mixture may of course contain neutral gas such as nitrogen, carbon dioxide or water vapor, so long as the amount of such neutral gas is not sufficient to make the mixture non-explosive.

What is claimed is:

1. The method of burning explosive gaseous mixtures, which comprise discharg-

- ing a stream of the mixture from a discharge orifice with a velocity greater than the rate of propagation of inflammation of the mixture and causing the stream of mixture to spread out with rapid reduction of its flow velocity, burning the mixture where its flow velocity is reduced to the rate of propagation of inflammation, and maintaining the temperature of the walls of the discharge orifice substantially lower than the ignition temperature of the mixture.
2. The method of burning explosive gaseous mixtures, which comprises discharging a stream of the mixture from a discharge orifice with a velocity greater than the rate of propagation of inflammation of the mixture and causing the stream of mixture to spread out with rapid reduction of its flow velocity, burning the mixture where its flow velocity is reduced to the rate of propagation of inflammation, and maintaining the temperature of the walls of the discharge orifice substantially lower than the ignition temperature of the mixture by withdrawing heat from the walls of the orifice with sufficient rapidity to prevent increase in temperature of the walls above the desired maximum.
3. The method of burning explosive gaseous mixtures, which comprises discharging a stream of the mixture from a discharge orifice with a velocity greater than the rate of propagation of inflammation of the mixture and causing the stream of mixture to spread out with rapid reduction of its flow velocity, burning the mixture where its flow velocity is reduced to the rate of propagation of inflammation, and maintaining the temperature of the walls of the discharge orifice substantially lower than the ignition temperature of the mixture by limiting the access of heat to the orifice and by withdrawing heat from the walls of

the orifice with sufficient rapidity to prevent increase in temperature of the walls above the desired maximum.

4. The method of burning explosive gaseous mixture, which comprises supplying the mixture to a discharge nozzle under pressure sufficient to cause the mixture to be discharged from the nozzle with a velocity greater than the rate of propagation of inflammation of the mixture, baffling the stream of mixture issuing from the nozzle to cause the same to spread out with rapid reduction of its flow velocity, burning the mixture, and maintaining the temperature of the walls of the discharge orifice of the nozzle substantially lower than the ignition temperature of the mixture.

5. The method of producing heat, which consists in combining fuel in a finely divided state with a combustion supporting gas in proportions to form an explosive gaseous mixture, supplying the mixture as it is formed to a discharge nozzle under sufficient pressure to cause a stream of the mixture to be discharged from the nozzle with a velocity greater than the rate of propagation of inflammation of the mixture, baffling the stream of mixture issuing from the nozzle to cause the same to spread out with rapid reduction of its flow velocity, burning the mixture, and maintaining the temperature of the walls of the discharge orifice of the nozzle substantially lower than the ignition temperature of the mixture.

In testimony whereof, we have hereunto set our hands, in the presence of two subscribing witnesses.
